UNITED STATES PATENT OFFICE.

ALBERT E. NOBLE, OF ANNISTON, ALABAMA.

CAR TRUCK.

Application filed October 10, 1921. Serial No. 503,756.

To all whom it may concern:

Be it known that I, ALBERT E. NOBLE, a citizen of the United States, residing at Anniston, in the county of Calhoun and State of Alabama, have invented certain new and useful Improvements in Car Trucks, of which the following is a specification.

This invention relates to car trucks and has for its principal object to provide a construction in which the load on the side frames will be received at the points below the journals; in which a conventional form of bolster can be used; and which will permit the bolster to be readily mounted and dismounted.

Further objects of the invention will become apparent as the description is read in connection with the accompanying drawing showing a selected embodiment of the invention, in which—

Fig. 1 is a side elevation;

Fig. 2 is a plan view of one side frame and a portion of the bolster; and

Fig. 3 is a transverse section taken on the line 3—3 of Fig. 1.

Referring to the drawing, 10 indicates arms adapted to rest on the journal boxes 11 in a well-understood manner. Extending downwardly from each of the arms and toward the middle of the side frame are the arch members 12 connected at their adjacent ends by a rectangular frame 13 which forms a housing for the springs and completes the arch of the side frame. The members 12 are preferably composed of a web 14 and flanges 15 and 16. These flanges 15 and 16 merge into the upright side pieces 17 of the rectangular frame 13. The bottom section 18 of the frame 13 is comparatively thin and relatively wide as indicated in Fig. 2, while the upper section 19 is relatively thick and also wide to provide sufficient stiffness to prevent buckling under the stresses of service. Extending upwardly from the rectangular frame 13 are a pair of columns 20 adapted to receive the bolster 21 and form a guide for the usual projections 22 on the bolster. To secure rigidity, I prefer to connect these columns with the arch members 12 by means of gussets 23. The spring pan 24 is normally seated on top of the cross piece 18 and because of the low arch of the side frame, I provide an off-set 25 in the pan to obtain greater road clearance. The springs 26 rest on the pan in the

usual manner, and seated on their upper ends are the spring caps 27 which carry the load from the bolster to the springs. These caps are allowed to reciprocate under the yielding action of the springs within slots 28 in the cross piece 19. In order to make this cross piece sufficiently strong, I have made the slots somewhat larger at the ends than at the central portions so that the cross piece 19 takes the form of three bars 29, 30 and 31 of substantially the form shown in Fig. 2. This construction places the greatest area of metal along the center of each of the bars 29, 30 and 31 where it is needed to prevent buckling.

From the foregoing it will be apparent that I have provided a very rigid and compact structure in which the load carried by the bolster is transferred to the side frames at points well below journals of the wheels, and in which the bolster of conventional construction can be readily mounted and dismounted.

The bar 18 of the rectangular frame 13 acts only in tension and therefore does not have to be thick or stiff, and the necessary metal to resist the strains can be secured by making it relatively thin as shown in Fig. 1 and wide, as indicated in Fig. 3. The cross piece 19 acts only in compression and may be called a strut. On this account it necessarily has to be both thick and wide enough to prevent buckling. By making it thick as in Fig. 1, and wide as shown in Fig. 2, I provide sufficient metal to give the desired stiffness and permit making the slots for the spring caps 27. The sides of the arch 12 being made of the webs 14 and the flanges 15 and 16 are very rigid and strong and make with the rectangular section 13 a very suitable arched structure which permits the columns 20 to be placed on top of the arch and left entirely disconnected at their upper ends so that the bolster may be freely mounted and dismounted. The gussets 23 brace the columns 20 and make it possible to use a very light section in the columns. The spring caps 27 are of sufficient depth to prevent the bolster coming in contact with the cross bar 19 in all ordinary service.

Various changes may be made in the form, construction and arrangement of the parts without departing from the spirit and scope of the invention, or sacrificing any of its material advantages, the form herein-

before described being merely a preferred embodiment thereof.

I claim:

1. A truck side frame comprising a casting having at its center a spring pocket which is open and unobstructed from the inner side to the outer side of the frame to permit the introduction and removal of a spring, and columns rising from the top 10 of the pocket, the space between the upper portions of the columns being open and unobstructed to permit of the downward insertion and upward removal of a truck bolster, the top of the pocket being provided with 15 an opening for the reception of a spring cap or plunger to support the truck bolster.

2. A truck side frame comprising a casting having at its center a spring pocket 20 which is open and unobstructed from the inner side to the outer side of the frame to permit the introduction and removal of a spring, and columns rising from the top of the pocket, the space between the upper portions of the columns being open and unobstructed to permit of the downward insertion and upward removal of a truck bolster, the top of the pocket being provided with 25 an opening for the reception of a spring cap or plunger to support the truck bolster, and a front arm and a rear arm inclined upwardly from the spring pocket and terminating in substantially horizontal portions to rest on journal boxes, the bottom of the 30 spring pocket being a tension member, and the top of the spring pocket being a strut or compression member.

3. A truck side frame comprising a casting having at its center a spring pocket 35 which is open and unobstructed from the inner side to the outer side of the frame to permit the introduction and removal of a spring, and columns rising from the top of the pocket, the space between the upper portions of the columns being open and unob- 40 structed to permit of the downward inser-

tion and upward removal of a truck bolster, a spring within the spring pocket, a spring cap working vertically through an opening 50 in the top of the pocket and supported on the spring, and a truck bolster working between the columns and supported on the spring cap.

4. A truck side frame comprising a cast- 55 ing having at its center a spring pocket which is open and unobstructed from the inner side to the outer side of the frame to permit the introduction and removal of a spring, and columns rising from the top of the pocket, the space between the upper portions of the columns being open and unob- 60 structed to permit of the downward inser- 65 tion and upward removal of a truck bolster, a spring within the spring pocket, a spring cap working vertically through an opening in the top of the pocket and supported on the spring, a truck bolster working between the columns and supported on the spring cap, and a front arm and a rear arm inclined upwardly from the spring pocket and 70 terminating in substantially horizontal portions to rest upon journal boxes.

5. A truck side frame comprising a casting having at its center a spring pocket 75 which is open and unobstructed from the inner side to the outer side of the frame to permit the introduction and removal of springs, columns rising from the top of the pocket, the space between the upper portions of the columns being open and unob- 80 structed to permit of the downward inser- 85 tion and upward removal of a truck bolster, the top of the pocket being provided with a plurality of openings, springs within the pocket and in alignment with the openings, spring caps working vertically through the openings in the top of the pocket and supported on the respective springs and a truck bolster working between the columns and supported on the spring 90 caps.

ALBERT E. NOBLE.
